UNITED STATES PATENT OFFICE.

FREDRIC C. WEIR, OF CINCINNATI, OHIO.

CABLE-RAILWAY CROSSING.

SPECIFICATION forming part of Letters Patent No. 398,202, dated February 19, 1889.

Application filed May 24, 1888. Serial No. 274,969. (No model.)

To all whom it may concern:

Be it known that I, FREDRIC C. WEIR, of Cincinnati, in the county of Hamilton and State of Ohio, have invented certain new and 5 useful Improvements in Cable-Railway Crossings, of which the following is a specification.

My invention relates to a crossing-frog composed of the center-bearing and slot rails which provides means for crossing all ordinary street-car rails over the slot-rails of the cable road.

The object of my invention is to provide strong and durable means for cheaply constructing such a crossing, the various features 15 of which will be set forth in the description of the accompanying drawings, making a part of this specification, in which—

Figure 1 is a top plan view of my invention. Fig. 2 is a line on x x , Fig. 1. Fig. 3 20 is a line on y y , Fig. 1. Fig. 4 is a line on z z , Fig. 1. Fig. 5 is an interior view, in elevation, of one of the slot-irons.

A B represent two slot-rails, which are made continuous, and secured to the bed of the 25 road in the usual manner. Their top flanges and webs are gained or cut away at a a , Fig. 1, so as to allow the passage of the flange of the street-car wheels.

C represents a center-bearing girder-rail. 30 A side-bearing rail could be used as well as the center-bearing rail here shown. These rails are cut at the desired angles, so as to have the beveled edge fit against the inclined webs of the slot-rails. They are secured to 35 these side rails by means of angle-plates 1, which are bent to fit, respectively, the under side of the flange B of the girder-rail and the webs of the slot-rails, to which they are secured by rivets 2 and 3. This strengthens 40 and supports the top of the rails.

To more securely hold the base of the rails in position, I provide an angle-plate, 4, which is projected at the bottom to pass under the

flange 5 of the girder-rail, as shown in Fig. 2, the upper angle of said brace 4 being bent to 45 fit the web of the slot-rail, to which it is secured by rivets 6.

7 represents a rivet passing through one of the flanges of the girder-rail and through the brace-plate 4, thus firmly securing the slot-rails to the girder-rails and holding them in 50 position vertically and laterally.

The angle-plates 1 might be omitted and still a good crossing secured.

In order to prevent the shank of the grip 55 from being caught on the corners of the slot-rails, which are gained to allow the passage of the flanges of the car-wheels, I provide guard-plates 8 on the under side of the flanges 9, as shown in Fig. 4, which plates serve as a 60 guide to the shank of the grip, and prevent such shank catching on the corners formed by the gains or cut-away portions a of the slot-rails.

Having described my invention, what I 65 claim is—

1. A crossing composed of the slot-rails A B, and the girder-rail C, beveled to fit said slot-rails, and secured to them by the brace-plate 4 and the rivets 6 and 7, substantially 70 as herein specified.

2. A crossing formed of slot-rails A B, and the girder-rail C, beveled to fit said slot-rails, and secured thereto by means of the brace-plates 1 and 4, bolted to the flange and web 75 of said rails, substantially as specified.

3. In combination with the rails A B, having the gains a , the guide-plates 8, secured to the under side of the flanges 9 of the rails A B, substantially as herein set forth. 80

In testimony whereof I have hereunto set my hand.

FREDRIC C. WEIR.

Witnesses:

ROBERT ZAHNER,
J. WATSON SIMS.
